UNITED STATES PATENT OFFICE.

GUSTAVE A. HENCKEL, OF NEW YORK, N. Y.

COMBINATION VASE AND CANDLESTICK.

1,109,751.

Specification of Letters Patent.

Patented Sept. 8, 1914.

Application filed March 18, 1914. Serial No. 825,535.

To all whom it may concern:

Be it known that I, GUSTAVE A. HENCKEL, a citizen of the United States of America, and a resident of New York, in the county 5 of New York and State of New York, have invented certain new and useful Improvements in Combination Vases and Candlesticks, of which the following is a specification.

10 My invention relates to improvements in candlesticks and comprises a hollow body adapted for use as a flower-vase or the like, and also as a holder for a candle or candle lamp, or the like.

15 My invention consists in the novel vase construction herein described, whereby the vase may be used both as a flower vase, or as a candle holder, and may also be used for both purposes simultaneously.

20 The objects of my invention are to improve vases and candle holders and to provide means whereby the same article may be used for both purposes, and, if desired, may be used for both purposes simultaneously; 25 also to provide a vase, adaptable for use also as a candle holder, which is capable of holding a candle or the like firmly, without interfering with its use as a flower holder, and which gives, externally, no indication of its 30 adaptability for use as a candle holder.

I will now proceed to describe my invention with reference to the accompanying drawings, and will then point out the novel features in claims.

35 In the drawings: Figure 1 shows an elevation and partial section of my combined vase and candle holder, and shows the same in use as a candle holder. Fig. 2 shows a top view of the said combined vase and 40 candle holder. Fig. 3 shows a central vertical section of the upper portion of the vase, and shows therein in central vertical section a candle socket. Fig. 4 shows a side elevation of the candle socket. Fig. 5 is a 45 detail sectional view illustrating an alternative support for the candle socket.

In the drawings, 1 designates the vase which, as customary, is a hollow body. The 50 particular configuration of this vase is of course immaterial to the present invention. At a suitable point in the interior of this vase, I provide an inwardly projecting flange 2.

55 3 designates a candle socket of hollow tubular form, preferably closed at the bottom as shown, and provided with a suitable

number of legs 4 connected, preferably, below the bottom of the socket 3, to a ring 5 adapted to rest upon the internal flange 2 of the vase and having, preferably, one or more 60 bayonet slots 6 adapted to coact with a pin or pins 7 projecting inward from the sides of the vase. The construction is such, as will be observed, that the flange 2 forms a seat for the base ring 5 of the candle socket 3; 65 but since the flange 2 projects inward a very short distance only, and since the ring 5 is entirely open, internally, and since the legs 4 connecting the socket 3 and ring 5 are narrow and spaced well apart, the vase 1 may 70 be used as a flower vase even while used also as a candle holder; for the stems of flowers and the like may be inserted into the vase through the openings between the legs 4 and through the open interior of the 75 ring 5.

Securing the ring 5 to the vase 1 by a bayonet joint or joints, as shown, is not an essential feature of my invention, but is convenient and desirable. When the candle 80 socket 3, with its base ring 5, has been removed from the vase 1, the latter is in effect an ordinary vase and adaptable for use as an ordinary vase.

As illustrated in Fig. 5, the vase 1 may be 85 provided with a support for the candle socket, consisting of a plurality of segmental projections 8, adapted to form supports for the base ring 5 in lieu of the continuous annular flange 2.

90 What I claim is:—

1. A combined flower holder and candle holder comprising a hollow body provided internally, at an intermediate point, with a flange projecting inwardly a short distance 95 from the inner wall of said hollow body, the said flange having a wide open center.

2. A combined flower holder and candle holder comprising a hollow body provided internally, at an intermediate point, with a flange projecting inwardly a short distance 100 from the inner wall of said hollow body, the said flange having a wide open center, in combination with a candle socket having a base adapted to rest on said flange.

105 3. A combined flower holder and candle holder comprising a hollow body provided internally, at an intermediate point, with a flange projecting inwardly a short distance 110 from the inner wall of said hollow body, the said flange having a wide open center, in combination with a candle socket having a

base adapted to rest on said flange, and means for locking such candle socket and hollow body together.

4. A combined flower holder and candle holder comprising a hollow body provided internally, at an intermediate point, with a flange projecting inwardly a short distance from the inner wall of said hollow body, the said flange having a wide open center, in combination with a candle socket having a base adapted to rest on said flange, the said base being open at the center and openings being provided between the candle socket and the base thereof, for the passage of flower stems and the like.

5. A combined flower holder and candle holder comprising a hollow body adapted to serve as a flower holder and a candle-supporting member having a base adapted to fit within said hollow body, such hollow body having a seat for said base, the said candle holder having openings for the passage of flower stems and the like.

6. A combined flower holder and candle

holder comprising a hollow body adapted for use as a flower holder, and having internally, in its upper portion, a support for a candle holder, and a candle holder adapted to rest on said support, said support provided with an opening for the passage of flower stems and the like.

7. A candle holder such as described, comprising a tubular socket, a ring-shaped base below such socket and having an opening through it, such base of larger diameter than the socket, and legs extending upwardly and inwardly from said ring-base to and in connection with the said socket and uniting the base and socket, openings being provided between the legs.

In testimony whereof I have signed this specification in the presence of two subscribing witnesses.

GUSTAVE A. HENCKEL.
